UNITED STATES PATENT OFFICE.

JOHN E. WEBSTER, OF PITTSBURGH, AND GEORGE M. EATON, OF WILKINSBURG, PENNSYLVANIA, ASSIGNORS TO WESTINGHOUSE ELECTRIC AND MANUFACTURING COMPANY, A CORPORATION OF PENNSYLVANIA.

APPARATUS FOR AND METHOD OF TEMPERING GEARS AND PINIONS.

1,253,315.

Specification of Letters Patent. Patented Jan. 15, 1918.

Application filed May 7, 1913. Serial No. 766,175.

To all whom it may concern:

Be it known that we, JOHN E. WEBSTER and GEORGE M. EATON, citizens of the United States, and residents, respectively, of Pittsburgh and Wilkinsburg, both in the county of Allegheny and State of Pennsylvania, have invented a new and useful Improvement in Apparatus for and Methods of Tempering Gears and Pinions, of which the following is a specification.

Our invention relates to methods of tempering or hardening gears and pinions, and to apparatus for practising the same.

One object of our invention is to simplify and improve the tempering of gear and pinion teeth and to provide an economical and expeditious method that shall insure a product of uniform excellence.

Another object of our invention is to provide inexpensive and simple apparatus that may be utilized expeditiously and with facility in practising our method.

In the prior art of tempering gears and pinions, it has been customary to plunge them, when hot, quickly into a bath of cool fluid whereby they become hardened and tempered to a greater or less extent throughout their mass. The difficulty with such a process resides in the fact that all of the teeth are not treated in precisely the same manner, and eddies, and gas pockets are likely to form between the teeth which prevent a uniform heat treatment of all portions thereof.

Moreover, the resulting products of the methods heretofore practised were not of uniform quality, because the temperature of the cooling bath and the length of time of immersion were governed only by the will of the operator. Inasmuch as these two factors were not predetermined, the results secured were not uniformly reliable and satisfactory.

According to our present invention, we propose to treat gears and pinions by subjecting the teeth to a cooling bath which shall flow longitudinally between them in an annular stream at a predetermined rate, the volume of the bath for each treatment being of a predetermined amount. By so doing, all portions of all of the teeth are treated in a like manner. Moreover, since the flow of the bath is longitudinally of the teeth, there is no possibility of an accumulation of steam

or gas pockets therein, for, in case gas tends to accumulate, it is immediately removed by the rapid flowing bath.

Our invention may be best understood by reference to the accompanying drawings, in which Figure 1 is a sectional view of a preferred form of apparatus for practising our invention; Fig. 2 is a similar view of a modified apparatus for accomplishing a similar result, and Figs. 3 and 4 are sectional views taken respectively on lines III—III and IV—IV of Fig. 2.

Referring to Fig. 1, a liquid-containing or storage tank 1 is provided with a float valve 2 of any well-known construction which governs the flow of water thereto from a supply pipe 3, in the usual manner. A pipe 4 projects downwardly from the tank 1 and the lower portion 5 thereof is of U shape and is submerged in a body of water 6 contained within the tank or receptacle 7. At a portion of the tube 4 that is normally submerged in the water 6, a gate valve 9 is provided that has a suitable operating mechanism 10 by means of which it may be adjusted. Any other suitable valve, of course, may be employed, although it is preferable to use a valve which is relatively quick-acting.

The end 11 of the pipe 4 is detachable and projects above the normal water level a distance substantially equal to the thickness of a pinion 12 to be treated, and within the tube 4 and somewhat below its extremity, is located a supporting and deflecting member 13. The member 13, which is mounted upon a centrally disposed rod 14, serves to support the pinion 12 to be treated and also constitutes a cone-shaped deflector having its apex pointing downwardly in order to definitely prescribe the course of the fluid which is employed for treating the pinion in the manner hereinafter set forth. It will be noted that the diameter of the end 11 of the pipe 4 is slightly greater than that of the pinion 12, whereby an annular passage 15 is provided around the pinion through which the cooling bath is caused to flow.

Usually, it will be desirable to place a muffle-plate 15^a over the central opening or bore 12^b of the pinion 12 to prevent the access of cooling fluid thereto, although, under certain conditions, it may be advisable to permit such access of fluid.

Assuming the various parts of the apparatus to occupy the positions shown, and the tank 1 and pipe 4 to be filled with fluid, and the pinion 12 to be heated to the desired 5 temperature, the operation of treating the pinion is as follows:

The valve 9 is first opened, thereby permitting the fluid contained in the pipe 4, and tank 1 to be forced by gravity upwardly 10 past the conical deflector 13 and through the annular opening 15 between the pinion teeth 12^a and the end 11 of the pipe 4 in a solid stream. Thus, all portions of the teeth 12^a are subjected to a predetermined quantity 15 of the cooling fluid for a predetermined length of time. The size of the tank 1, or at least the amount of water contained therein, will be so chosen that the treatment of the pinion 12 may be completed when the 20 water in the pipe 4 has fallen to a height which corresponds to the upper extremity of the free end 11 of the tube 4. After this condition obtains, the excess water above the normal water level of the tank 7 is drained 25 from the tube 4 through a suitable opening or leak hole 16 provided for that purpose. The level of the water in the tube 4 is thus reduced to correspond to that of the water outside the tube. The valve 9 may then be 30 closed and the treated pinion 12 removed and replaced by another one, it being understood that, in the meantime, the tank 1 and the pipe 4 are refilled to the desired amount. The apparatus is then in readiness for a 35 similar treatment of another pinion.

Reference may now be had to Figs. 2, 3 and 4 in which the cooling fluid within the tank 1 is allowed to act upon the pinion 12 to be treated as it descends through the pipe 40 4 into a suitable drain 17. In this case, the pipe 4 is provided with a valve 18 of the gravity type which may be operated through a suitable mechanism 19, and the pinion 12 is adapted to be supported in position upon 45 a pivotally mounted bracket arm 21 which is adapted to swing into proper relationship with the tube 4.

The tube 4 comprises two sections 4^a and 4^b which are telescoped together at an intermediate point to permit of relative movement 50 between the lower section 4^b and the pinion 12. A pivotally mounted handle 22 is provided with a yoke portion 23 which straddles the pipe 4^b and cooperates with 55 suitable pins 24 therein in such manner as to effect a vertical movement thereof when properly operated by the attendant. The cone-shaped deflector 13 is attached rigidly within the lower portion of the tube 4 by 60 suitable supports 25 and is adapted to rest

upon the upper surface of the pinion 12 when the apparatus is in operative condition. Without a detailed description of the operation of this modified type of apparatus, it will be understood that, upon opening the valve 18, the fluid in the tank 1 is allowed to descend through the pipe 4 and to pass longitudinally between the teeth 12^a of the pinion 12 in an annular stream at a rapid rate, thereby tempering or hardening 70 the teeth 12^a to any desired degree, according to the amount of cooling fluid and the temperature thereof.

It will, of course, be understood that our method of tempering gears and pinions is 75 not dependent upon any particular apparatus and that the forms herein illustrated are merely convenient commercial types of apparatus by which our method may be practised. We desire that only such limitations shall be imposed as are indicated in the appended claims.

We claim as our invention:—

1. The method of uniformly tempering pinions which consists in causing a predetermined volume of fluid to pass longitudinally along the teeth in an annular stream at a predetermined rate.

2. The method of treating gears which consists in causing a predetermined volume of fluid to pass longitudinally along the teeth thereof in a uniformly distributed stream.

3. An apparatus for treating toothed gears comprising means for supporting a gear and means for flowing a predetermined volume of cooling fluid between the gear teeth at a predetermined rate.

4. An apparatus for treating toothed gears comprising a liquid-receiving tank, a U-shaped pipe partially submerged in the liquid within said tank, means for supporting a gear within one end of said pipe and just above the liquid level and means for discharging a predetermined volume of liquid into the opposite end of said pipe.

5. The combination with a U-shaped pipe, and means within one end thereof for supporting a gear centrally in position, of means for discharging a predetermined volume of cooling fluid into the other end of said pipe.

In testimony whereof, we have hereunto subscribed our names this 30th day of April, 1913.

JOHN E. WEBSTER.
GEORGE M. EATON.
